UNITED STATES PATENT OFFICE.

JAMES V. HOQUE, OF LONG BEACH, CALIFORNIA.

DIRECTION-INDICATOR FOR MOTOR-DRIVEN VEHICLES.

1,322,239.

Specification of Letters Patent. Patented Nov. 18, 1919.

Application filed March 3, 1919. Serial No. 280,413.

To all whom it may concern:

Be it known that I, JAMES V. HOQUE, a citizen of the United States, residing at Long Beach, in the county of Los Angeles and State of California, have invented new and useful Improvements in Direction-Indicators for Motor-Driven Vehicles, of which the following is a specification.

My object is to make a direction indicator for motor driven vehicles, and my invention consists of the novel features herein shown, described and claimed.

Figure 1 is a fragmentary view of a motor driven vehicle provided with direction indicators in accordance with the principles of my invention.

Fig. 2 is a fragmentary detail of one of the direction indicators, parts being shown in section.

Fig. 3 is a diagrammatic view of the electric circuits used in the direction indicators.

The pipe casing 1 is mounted behind the instrument board 2 and preferably near its top and rigidly connected to the side bars 3 and 4 of the wind shield by clips 5 and 6. The indicators 7 and 8 extend from the ends of the casing 1. The clips 5 and 6 and the indicators 7 and 8 are substantially alike, and in Fig. 2 I have shown the details of the clip 5 and the indicator 7. The pipe 1 has a longitudinal slot 9 extending through one wall and a notch 10 extends forwardly from the outer end of the slot 9, and a similar notch 11 extends backwardly from the inner end of the slot 9 so as to make a double bayonet slot.

A hollow supporting arm 12 has a sleeve 13 fixed upon its inner end, and the sleeve 13 slides in the opening 14 in the casing 1. A coil spring 15 is placed upon the supporting arm 12 and attached to the supporting arm at its inner end by a pin 16. A sleeve 17 is fixed in the extreme outer end of the casing 1, and the fixed end 18 of the spring is rigidly attached to this sleeve, and the supporting arm 12 slides freely through the sleeve. A handle 19 has a stem 20 inserted through the bayonet slot and screwed into the supporting arm 12. An electric conductor 21 is inserted through the supporting arm 12 and upwardly through the stem 20 and connected to the contact 22. The lamp casing 23 is fixed upon the outer end of the supporting arm 12. A lamp 24 is mounted in the casing and the conductor 21 is con-

nected to the lamp 24 and the lamp is ground. An indicator disk 25 is connected to the casing 23 the face of said disk being preferably painted red.

When the handle 19 is operated to bring the stem 20 into the notch 11 the disk 25 is horizontal and the indicator is out of use. When the operator kicks the handle 19 upwardly the tension of the spring 15 will throw the stem 20 outwardly in the slot 9 and rotate the supporting arm 12 until the stem 20 moves into the notch 10 thereby throwing the signal disk 25 to a vertical position and extending the disk outwardly from the side of the automobile. The battery 26 has a ground 27 and the outer end of the battery is connected by a conductor 28 to the binding post 29, and the binding post 29 is connected to the casing 1 by a bracket 30 and has a contact member 31 in position to be engaged by the contact member 22, so that when the disk 25 is moved outwardly and turned to a vertical position, the circuit is closed through the contact members 22 and 31 to illuminate the lamp, and so that when the handle 19 is operated to return the indicator to its normal position the circuit is broken.

The clip 5 has a bearing member 32 formed by bending a piece of strap iron around the casing and connecting the ends together by a screw 33 so as to clamp the end of the casing 1, and a twisted arm 34 extends upwardly from the bearing 32. The clamp members 35 and 36 are adapted to engage the side bar 3 of the wind shield, and said clamping members are connected together by screws 37, and the arm 34 is rigidly connected to the clamping members 35 and 36. The clip 6 is identical with the clip 5, and the clips 5 and 6 serve to rigidly connect the casing 1 to the automobile. The indicator 8 is identical with the indicator 7 and the two indicators are independent of each other, so that one extends to the right and the other to the left.

The casing 23 and indicator disk 25 are arranged so that when the lamps are burning and the disk is in vertical position the lamps will be visible from the back and front.

Various changes may be made without departing from the spirit of my invention as claimed.

I claim:

In a direction indicator for vehicles, in

combination, a casing mounted horizontally on the instrument board and transversely of the vehicle having a longitudinal slot at the ends of which are notches cut in opposite directions transversely of the longitudinal slot, a supporting arm slidably mounted in the casing, an indicator mounted upon the outer end of the arm designed to indicate when positioned with the arm projecting outwardly and not to indicate when the arm is positioned inwardly and turned one-fourth of the revolution, a handle to operate the arm positively fixed thereto and extending outwardly through the slot adapted to be positioned at the will of the operator in one of the transverse notches whereby the indicator may be positioned inwardly and

turned horizontally so as not to indicate or in the other transverse notch whereby the indicator may be projected outwardly and turned vertically so that it will indicate, a spring within the casing one end of which is fixed to the casing and the other end fixed to the supporting arm, the normal position of the spring being when the supporting arm is positioned with the operating handle midway of the longitudinal slot whereby when the handle is positioned in a transverse notch the spring is compressed to hold the handle in the notch and an indicator upon the outer end of the arm.

In testimony whereof I have signed my name to this specification.

J. V. HOQUE.
